EDWIN E. SAVARD AND WINFRED E. JONES, OF ROCHESTER, NEW YORK.

TIMER FOR GAS ENGINES.

977,752.

Specification of Letters Patent.

Patented Dec. 6, 1910.

Application filed September 22, 1909. Serial No. 518,970.

To all whom it may concern:

Be it known that we, EDWIN E. SAVARD and WINFRED E. JONES, both of Rochester, in the county of Monroe and State of New York, have invented a new and useful Improvement in Timers for Gas-Engines, which improvement is fully set forth in the following specification, and shown in the accompanying drawings.

10 This invention relates to certain new and useful improvements in timers for automobiles and more particularly to a timer which is adapted for use in connection with gas or gasoline engines or similar machines 15 for exploding the gas mixture in the cylinder or cylinders of said machine by an electric spark, at the proper time.

It has for its objects among others to provide a simple and efficient timer readily applied to the timer shaft of an engine to revolve therewith and adapted for use in connection with a gas or gasoline engine or the like having any number of cylinders.

Another object of the invention is to provide a non-revolute annular contact plate or ring mounted for coöperation with and adapted to touch successively a plurality of spring-pressed balls and move directly away from the same after the contact is made so 30 that there is practically no wear upon the parts, thus constituting an essential improvement over the wiper contacts now employed. The annular contact plate or ring is mounted so as to be free to move in any 35 direction in a plane, being engaged only by an eccentric which does not revolve said annular contact plate or ring but merely pushes it, at it were, laterally against and then draws it away from the balls in succession without any draw or wipe motion 40 against the balls. Means are provided for proper adjustment, and the device, as a whole, is of such a simple nature as to permit of ready assemblage of its parts and its 45 application to the machine and, at the same time, it is durable, efficient and reliable in its action.

Other objects and advantages of the invention will hereinafter appear and the 50 novel features thereof will be particularly pointed out in the appended claims.

The invention is clearly illustrated in the accompanying drawings, which, with the numerals of reference marked thereon, form 55 a part of this specification, and in which—

Figure 1 is an end elevation of the im-

proved device applied to the shaft of an engine. Fig. 2 is a substantially central longitudinal section through the same. Fig. 3 is a detail in perspective with portions 60 broken away and parts in section. Fig. 4 is a perspective view of the eccentric and the annular ring removed.

Like numerals of reference indicate corresponding parts in the several views. 65

Referring to the drawings, 1 designates the timer shaft of a gas or gasoline engine or other machine to which the timer is to be applied. The timer, in its preferred form, comprises a hub 2 having a socket 3 for the 70 reception of the end of the shaft 1 to which it is designed to be adjustably and detachably secured in any suitable manner, as by set screws or the like 4. This hub has a concentric extension 5 which, at its upper 75 end, has an eccentric extension 6 with an annular groove or channel 7 for a purpose which will soon be made apparent.

80 8 An annular cup-shaped member having the flange portion 9, said cup being of metal or any other suitable material and in said flange or rim portion 9 are a plurality of openings, extending radially with relation to its hub portion, in this instance, being shown as four in number, and within each hole or opening 10 is placed an insulating ring 11 which is retained therein, preferably by frictional engagement with the walls of the opening, and within this insulating ring is threaded, or otherwise retained, a sleeve 12, the inner end of which is slightly turned inwardly, as shown at 13, so as to retain therein a ball 14, the construction being such as to prevent the ball from passing entirely through, but permitting a portion thereof to 95 project beyond the inner end of the sleeve, as seen clearly in Figs. 1 and 2, so as to be in position to be contacted by the annular ring or contact plate, soon to be described. A spring 15, arranged within the sleeve, exerts its influence against the ball and serves to normally keep the latter forced to the inner end of the sleeve so that it projects a sufficient distance therebeyond, as seen clearly in Figs. 1 and 2. 100 105

16 is a cap having threaded engagement with the threads of the sleeve by reason of the flanged portion 17 of the said cap and projecting centrally from this cap is a screw-threaded stud or shank 18 which receives the two nuts 19 and 20 which serve to hold the cap in place and serve also as means for 110

attachment of the wires for the usual purposes.

The hub 21 of the nut-like member 8 has an axial bore 22 in which is received the 5 metallic bushing 23 in which is received the cylindrical concentric portion 5 of the hub 2, as seen clearly in Fig. 2.

Sleeved on the eccentric portion 6 is the disk 24 having a side portion flattened, as at 10 25, and bored radially to receive a set screw or the like 26, the inner end of which is adapted to engage in the annular groove 7 of the eccentric portion 6 of the hub 2. This disk 24 has a concentric bore 27 and an eccentric extension 28 through which said bore extends. 29 is a disk or ring having a concentric bore 30 in which fits the eccentric portion 28, as seen clearly in Fig. 2.

Projecting from the cup portion 8 parallel 20 with the bore thereof is a pin 31 having an opening for the reception of a spring cotter pin or the like 32. To this pin is designed to be attached a lever (not shown) disposed for manipulation by the operator 25 for controlling the position of the cup for changing the time of contact.

With the parts constructed and arranged substantially as hereinbefore described and as clearly illustrated in the drawings, the 30 operation will be apparent. In the revolution of the parts, the annular contact plate or ring 29 is thrown out by the action of the eccentric 28, which latter coming in contact with the ball in the retainer, contact is made 35 through the usual electric connections and, by reason of the construction of the parts and the fact that the said ring does not revolve but is merely pushed out by the eccentric coming in contact with the ball of 40 the retainer and remaining still until it is drawn away by the motion of the eccentric and then carried to the next point of contact, all friction is thrown on the eccentric and consequent wear of the contact points 45 is avoided.

We can easily and quickly lengthen or shorten the time of contact so as to produce a long or short spark, by reason of the tip of the shaft carrying the eccentric being 50 thrown out of center and by placing the eccentric at different positions on the shaft so that the length of stroke is changed from any point between minimum and maximum, it being understood that a long stroke will 55 put the ball farther back in the retainer and being longer in contact, a longer spark is consequently produced. The length of contact is changed by changing the position of the eccentric carrying the contact ring on 60 the eccentric extension of the shaft, which lengthens or shortens the stroke. Furthermore, by reason of the contact being made by a stroke nearly direct from the center, there is no tendency to change the position 65 of the cup member as there would be by a

wiping stroke and, consequently, there is no strain on the controlling lever attached to the pin 31 that controls the position of the cup.

When the ring 29 comes in contact with a 70 ball, the circuit is completed and the current passes through the ball retainer and ball to the ring 29 and thence to the cup 8 and to a ground wire fastened to the top of the cover to such cup (which latter is removed 75 for the sake of clearness) or any suitable place, completing a circuit through the usual mechanism and firing or exploding the gas in the cylinder connected with that particular point of contact. As the ring 29 is 80 brought into contact with the next ball, the operation is repeated and explosion takes place in the cylinder corresponding to said ball.

The parts are readily adjusted, the operation is reliable and the device, as a whole, is most efficient for the purposes for which it is designed.

Modifications in detail may be resorted to without departing from the spirit of the invention or sacrificing any of its advantages.

What is claimed as new is:—

1. In a timer for gas engines, a shaft, an eccentric presenting a large wearing surface, an eccentric extension on said shaft, a contact disk carried by said eccentric, a rim and contacts adjustable therein, the said eccentric being adjustable on the eccentric extension to vary the length of contact.

2. In a timer for gas engines, the combination with a shaft, of an eccentric presenting a large wearing surface, the shaft having an extension eccentrically disposed with relation to said eccentric and a contact disk carried by said eccentric, the said eccentric being shiftable on said eccentric extension to lengthen or shorten the stroke.

3. In a timer for gas engines, the combination with a shaft having a concentric portion and an extension eccentric with relation thereto, of an eccentric on said extension presenting a large wearing surface, means for adjusting the length of stroke or time of contact, a rim, and fixed rim contacts carried thereby and with relation to which said eccentric is adjusted on the eccentric extension, said rim contacts being fixed in position after once set.

4. In a timer for gas engines, the combination with a shaft, of an eccentric presenting a large wearing surface, the shaft having an eccentric extension carrying said eccentric, means for changing the length of stroke or time of contact, fixed rim contacts with relation to which said eccentric is adjusted on said eccentric extension, and means for simultaneously moving all of said contacts.

5. In a timer for gas engines, the combination with a shaft having a concentric ex- 130

tension and an extension eccentric thereto, of
a cup-shaped member on said concentric ex-
tension, ball contacts carried by the rim por-
tion of said member, a disk sleeved on the
5 eccentric extension, said disk having a con-
centric bore and an eccentric extension
through which said bore extends, and a disk
having a concentric bore in which said ec-
centric portion fits.

In witness whereof, we have hereunto set 10
our hands this 20th day of September, 1909,
in the presence of two subscribing witnesses.
